DESIGN FOR A SHOE COVERING OR SIMILAR ARTICLE

Jerome J. Dorfman and Frank H. Kennedy,
New York, N. Y.

Application March 18, 1949, Serial No. 1,464

Term of patent 14 years

(Cl. D7—4)

To all whom it may concern:

Be it known that we, Jerome J. Dorfman and Frank H. Kennedy, citizens of the United States of America, and residents respectively of city of New York, county and State of New York, have invented a new, original, and ornamental Design for a Shoe Covering or Similar Article, of which the following is a specification, reference being had to the accompanying drawing, forming part thereof.

Fig. 1 is a front perspective view of a shoe covering or similar article showing our new design, and

Fig. 2 is a bottom plan view thereof.

The opposite side of Fig. 1 is substantially the same as that shown in Fig. 1.

We claim:

The ornamental design for a shoe covering or similar article substantially as shown and described.

JEROME J. DORFMAN.
FRANK H. KENNEDY.
